UNITED STATES PATENT OFFICE

2,535,691

VENTILATED WALL AND FLOOR

Mark Miller, Jacksonville, Fla.

Application October 11, 1946, Serial No. 702,805

1 Claim. (Cl. 72—1)

1

This invention relates to a novel construction of molded blocks adapted for use in the construction of walls of concrete or similar material and has particular reference to a construction of building blocks to afford a ventilation of the walls and a circulation of air through the floors of the building maintaining the walls in a dry condition so that paint or plaster will adhere thereto and to prevent rotting of roof timbers at their points of contact with the walls.

A still further object of the invention is to provide a novel building block which will facilitate the circulation of air through the walls and floors of concrete or similar construction for tending to cool the building during the summer and for heating the building during the winter.

Various other objects and advantages of the invention will hereinafter become more fully apparent from the following description of the drawings, illustrating the preferred embodiment thereof, and wherein:

Figure 1 is a bottom plan view of a building block constructed in accordance with the invention;

Figure 2 is a side elevational view thereof;

Figure 3 is a longitudinal sectional view showing the block disposed in abutting engagement with adjoining blocks, shown in dotted lines;

Figure 4 is a side elevational view, partly in vertical section and showing the blocks in applied position and in conjunction with a modified construction of a floor, especially adapted for use therewith;

Figure 5 is an enlarged vertical sectional view of a portion of the floor and wall as seen in Figure 4;

Figure 6 is a fragmentary side elevational view of a portion of a slightly modified form of the building block, and

Figure 7 is a vertical sectional view thereof taken substantially along a plane as indicated by the line 7—7 of Figure 6.

Referring more specifically to the drawings, numeral 8 designates generally an improved construction of building block which may be formed of any suitable material such as concrete, tile or the like which includes corresponding side walls 9 connected at spaced intervals by transverse webs 10 which combine with said side walls to form openings 11 which extend vertically through the block 8 when in its normal upright position, as seen in Figure 2. The bottom edges of the side walls 9, intermediate of the webs 10, are provided with notches 12 which are preferably V-shaped and the ends and bottom edges of the

side walls 9 are beveled, as seen in 13 to combine with an abutting block 8, of corresponding construction, to form an additional notch, corresponding to the notches 12 at each end of each of the blocks 8. Further, the side walls 5 protrude slightly beyond the outermost webs 10 so that when the blocks 8 are arranged in courses with the ends of the side walls abutting, as illustrated in full and dotted lines of Figure 3, the adjacent webs 10 of adjacent blocks 8 and the protruding ends of the side walls 9 will combine to form vertical passages 14 with which the notches formed by the beveled edges 13 communicate.

Figure 4 illustrates a portion of a building 15 wherein a foundation or footing member 15 is embedded in the ground to support a wall 16 forms a plurality of courses of building blocks 17 and 8. The building blocks 17 differ from the building blocks in that said blocks 17 are not provided with notches 12 or beveled surfaces 13 in the lower edges of the side walls thereof. The course of the building blocks 8 is disposed so that the bottom edges of the blocks 8 will be located intermediate of the upper and lower surface of each floor 18 which abuts against the wall 16 and which floors 18, only one of which is illustrated in Figure 4, are likewise formed of concrete, tile or other similar material. The floor 18 is provided with conduits or passages extending therethrough and which may be formed by pipes 19 molded into the floor 18, as seen in Figure 4, the ends of which project into the notches 12 so that the bores of the pipes 19 will be in communication with the passages formed by aligned openings 10 of the blocks 8 and 17. If preferred, the floor 18 may be molded with bores extending therethrough the open ends of which are in communication with the notches 12 or the notches formed by the beveled edges 13 and also, if desired, said notches 12 and those formed by the beveled surfaces 13 may be of various shapes to conform to the size and shapes of the passages in the floor with which they communicate.

45 It will likewise be readily obvious that the wall formed by the blocks 8 and 17, as illustrated in Figure 4, may be either an inside or an outside wall of a building of which it forms a part, and if an inside wall, floor 18 will abut against the 50 opposite side thereof and will be disposed so that pipes 19 or passages extending therethrough will communicate with the passages 11 by means of the notches 12 or the notches formed by the surfaces 13.

55 In addition to a course in the wall formed by

blocks 8 located at the bottom edges thereof contiguous with each of the floors 18, the upper course of the wall and which is disposed beneath the roof 20 is also formed by blocks 8 and the notches thereof open either outwardly of the building or into the air chamber between the ceiling of the top floor of a building and the roof 20. It will then be readily apparent that air will circulate freely through the passages in the floors 18, to and from the passages formed by the aligned openings of the blocks 8 and 17 so that, under hot weather conditions, hot air can pass upwardly through the passages of the walls and from the passages in the floors for cooling the building. Under cold weather conditions, the air chambers formed by the passages in the walls and floors will assist in insulating the building and the hot air passing outwardly through the floor passages and upwardly through the wall passages will tend to heat the floors and walls to thus afford a supplemental indirect heating system. The courses formed by the blocks 8 which constitute a part of the outer walls of the building may have the notches 12 and 13 on the outer sides of the walls closed, if desired, but such notches are preferably left open in order to facilitate the cooling of the building under hot weather conditions. Should the courses of the walls formed by the blocks 8 pass over windows or doors, the notches 12 and 13 may be closed with mortar or cement so that the air passing upwardly through the passages in the blocks will be released therefrom only from the notches of the upper course of the blocks 8 and beneath and adjacent the roof 20.

The notches forming communicating passages to and from the openings or passages 14 through the blocks 8 may obviously be made in various shapes, other than illustrated in Figures 1 to 5, such as circular or substantially circular as indicated at 21 in Figures 6 and 7, wherein a slightly modified form of block, designated generally 8a, is illustrated. The blocks 8a differ from the blocks 8 only in that they are provided with circular openings 21 in lieu of the notches 12. In Figures 6 and 7 the openings 21 are shown covered with mesh wire fabric to prevent insects

from passing therethrough and into the passages of the blocks or floors and it will be readily obvious that the notches of the blocks 8 could be similarly covered with wire fabric for the same purpose.

Various modifications and changes are contemplated and may obviously be resorted to, without departing from the spirit and scope of the invention as hereinafter defined by the appended claim.

10 I claim:

A building wall and floor construction comprising a wall formed of a plurality of courses of blocks each course including a plurality of blocks each having extensions at each end of the inner and outer faces thereof, the extensions of the adjacent blocks of the same course abutting, vertical passages formed in the wall by said extensions and end portions of the blocks, located between said extensions, certain of the abutting, complementary extensions having beveled corners, lateral passages, formed by said beveled corners, communicating with the vertical passages, a floor having an edge overlapping and abutting two of the courses of blocks, and air passages in the floor having ends opening outwardly of said edge and registering with said lateral passages.

30 MARK MILLER.
